UNITED STATES PATENT OFFICE

CHARLES SCOTT-SNELL AND EDWARD SCOTT-SNELL, OF LONDON, ENGLAND, ASSIGNEES
TO INTERNATIONAL VACUUM POWER, LIMITED, OF LONDON, ENGLAND

THERMALLY-ACTUATED MOTIVE DEVICE

Application filed January 11, 1930, Serial No. 420,265, and in Great Britain January 12, 1929.

This invention relates to thermally actuated motive devices wherein heat is continuously supplied to a vapor generator which is in communication by way of suitable valves 5 with an inlet and an outlet duct communicating respectively with a supply of liquid and with apparatus to which it is desired to convey the said liquid, a pressure or velocity head being produced in the liquid by automatic action.

Examples of such devices are included in United States specification No. 1,773,551. We have found that when such devices are applied in practice in connection with the feeding of oil under pressure to oil nozzles there is a limit to the pressure which can be derived from the system amounting to about 20 or 25 lb. per square inch. In some cases it is desirable to employ higher delivery pressures and the object of the present invention is to provide means for the attainment of such pressures.

The attached diagrammatic figure illustrates one convenient mode of carrying the present invention into effect. According to this figure we provide a vapor generator *m* which is closed at its lower end and bent over to form a U-tube, the other limb *n* of which is connected to a vertical conduit 30, the upper end 20 of which is connected by way of an uptake pipe *o* of small cross-sectional area as compared with that of the U-tube *m*, *n* to the vapor generator *m*, the connection of the latter being at a point somewhat below the upper end thereof. The upper end 20 of the vertical pipe 30 is also connected by a pipe 31 with the upper end of a further vertical pipe *p*, the lower end of which is connected by way of a duct 21 with the pipe 30 as shown. The lower end of the pipe *p* is furnished with a non-return inlet valve 32, while the upper end of this pipe *p* is furnished with a non-return delivery valve 33.

The vapor generator is furnished with a strip 15 of heat-conducting material such as brass which is intended to rest continuously in a flame or other source of heat.

In operation, so long as heat is continuously supplied to the tube *m* by way of the strip 15 a recurring cycle is produced as fol-

lows:—Vapor is generated into the generator *m* and at the same time liquid is delivered past the valve 33 and after a time interval is ejected through the tube *p*. The vapor, however, before it reaches the tube *p* for condensation is caused to travel by way of the upper end 20 of the tube 30, the slight delay occasioned thereby being sufficient to ensure substantial uniformity of the temperature of the liquid in the generator *m*. When condensation of the vapor rising through the pipes *o* and 31 does take place none of the liquid in the pipe *m* is of such a high temperature as will enable it to boil and thus the full effect of the pressure drop resulting from condensation is utilized in drawing in fresh liquid past the valve 32.

It will be appreciated that before heat is supplied to the strip 15 the apparatus is completely full of liquid, while so long as heat is applied to the strip there is an automatic delivery of oil past the valve 33 with a corresponding influx of oil by way of the valve 32.

Having now described our invention what we claim as new and desire to secure by Letters Patent is:—

1. A thermally actuated motive device including a liquid-containing conduit, a non-return delivery valve at the top thereof, a non-return admission valve at the bottom thereof, a continuously heated inverted U-shaped conduit, the open end of one limb of which is connected to said former conduit at a point adjacent its lower end and above said admission valve, a condensation delay chamber and a conduit of smaller bore than that of said U-shaped conduit connected between the other limb thereof and said condensation delay chamber and between said latter chamber and a point adjacent said upper end of the first-mentioned conduit and below said valve.

2. A thermally actuated device as claimed in claim 1 wherein said condensation delay chamber comprises a tubular space for the retention of vapor after its ejection from said inverted U-shaped conduit and prior to its condensation.

3. A thermally actuated device as claimed
